UNITED STATES PATENT OFFICE.

JOHN STRAKA, OF KENT, OHIO, ASSIGNOR TO THE WAHL COMPANY, OF WILMINGTON, DELAWARE, A CORPORATION OF DELAWARE.

MAGAZINE PENCIL.

Application filed August 16, 1922. Serial No. 582,142.

This invention relates to mechanical pencils.

The invention has special reference to a tip unit, including a normal tip and an extension therefrom, adapted to serve as a lead support and guide, and also, as a support for the lead propeller and as a co-active agent in connection with the operation of the latter, to advance the lead, and also, including the 10 fashioning of the extension member to permit entry, through its rearward end portion, of a lead section and lead propeller. The invention also includes a main body portion for ready detachable union with the tip unit 15 and the provision of a clearance way therein for the entry of the extension portion of the tip thereinto and a relative fashioning of the propeller and the wall of the clearance way in the body member for such engagement 20 that, through relative turning of the tip and body, the propeller will be advanced within the extension member of the tip to cause projection of the lead section.

The invention also includes an interior 25 fashioning of the main body portion of the pencil to afford a clearance opening for the entry of extra lead sections, and a cap closure for the rear end of the body portion.

The invention also includes details of 30 structure and combination of parts herein-after more particularly specified.

Referring to the drawings, Figure 1, is a side elevation showing the parts of my invention completely assembled.

35 Figure 2, is a detail view, showing the fashioning of a shell member, adapted for insertion within the main body portion of the pencil.

Figure 3, is a transverse section on the 40 line 3—3 of Fig. 1.

Figure 4, is a transverse sectional view on the line 4—4 of Figure 2.

Figure 5, is a detail view of a tip unit including a tip member and an extension 45 therefrom and showing the manner of support and entry of a lead section and a lead propeller.

Figure 6 is a central longitudinal section 50 showing the interior construction and assembly of parts.

Referring to the drawings, 10, is a perforated tip member. 11, is an extending actuator member integrally connected therewith, the same being centrally perforated in 55 register with the perforation in the main tip

member and is fashioned throughout a portion of its length with the spiral way 12. 13, is a tensioning member rigidly united to the tip unit at one end but having resilient free ends active to permit detachable frictional 60 rotatable connection between the tip and pencil body. The member 13, as herein shown is adapted to co-act in connection with a metal body and for that reason is fashioned with longitudinal slots to permit resilient action. However, should it be desired to join the tip unit to a wood or fiber body, such a resiliently acting member would not be required, as a mere shouldered portion upon the tip unit would function in connection with 65 such wood or fiber body for detachable frictional union.

14, is a hollow barrel forming the main pencil body and 15, is a cap closure therefor.

16, refers generally to an inner tube or 70 shell member, adapted for insertion within and removable from the pencil body, as shown in Fig. 4 the lower portion 17, thereof being interiorly fashioned to present plural longitudinally extending guide ways 18, for 75 coaction with a lead propeller as hereinafter particularly described, and 20, is an extra lead container portion of the shell. A pocket clip 24 as shown is removably held between the hollow barrel and inner tube with the upper end of the clip seated in the depression 80 25 formed in one of the faces of the shell 16.

Referring now to means for advancing a lead section, 21, to exposure at the end of the tip, 22, is a lead propeller adapted for entry 90 within the tip extension member 11, and is fashioned with a laterally projecting member 95 as 23, adapted for co-action with the spiral way 12, in the extension member and also with any one of the corrugated ways 18, in the member 17, of the shell 16. The extra leads may be stored either within the hollow inner shell 16 or in the clearance spaces between the exterior valleys of the corrugations 18 and the body 15 as desired.

When the tip unit is joined to the pencil body, the extension member 11 thereof, will be entered within portion 17, of shell member 16, with the laterally projecting member 23, lying within one of the corrugations 18, 100 whereby, upon relative turning between the tip unit and the body portion of the pencil, the propeller will be turned, and through the co-action of said laterally projecting member 105 with the spiral way 12, in extension member 110

11, the lead propeller may be advanced or retracted within the pencil body according to the direction of relative turning of said tip and body members, and in such action projecting member 23, will slide forwardly or rearwardly within one of the longitudinal corrugated portions 18 of the shell. The inner shell member is shown in Fig. 2 in the same relative position longitudinally with respect to Fig. 1 that it will occupy when inserted in the pencil body or barrel 14.

While I have shown the lead propeller provided with a laterally projecting portion at its rear end as exemplifying my preferred form of construction, nevertheless, I have in conception that such a lug extension may be provided at an intermediate point in its length for co-action with the spiral way 12, in extension member 11 and that a similar projecting member may be fashioned on the propeller at the rearward portion thereof for co-active relationing with the corrugated portions 18, of the shell portion 17. The eraser holder shown in Fig. 6 is inserted in the upper end of the inner shell member 16 and functions to form a closure for the upper end of the extra lead container and also hold a rubber for erasing purposes.

In the structure herein presented I have directed thought to the development of a simple and cheap pencil structure comprising a tip unit and main body portion that may be frictionally joined, to the end of ready separation, also, to the simple union of the lead and lead propeller support with the tip to the end that by mere separation of the tip unit and main body member, ready access is had for the entry of lead sections by the mere removal of the lead propeller pin from the tip unit and whereby, mere joining action of the tip unit to the main body, puts the pencil in condition for operative functioning.

More or less variation of the exact details

of construction is possible without departing from the spirit of this invention; I desire, therefore, not to limit myself to the exact form of the construction shown and described, but intend, in the following claims, to point out all of the invention disclosed herein.

I claim as new and desire to secure by Letters Patent:

1. In a mechanical pencil, a hollow barrel forming a handle portion, an inner tube in said hollow barrel of reduced cross-sectional area at one end, a tip rotatably and removably secured at one end of said barrel, an extension on said tip adapted to extend into the reduced end of said inner tube, a lead propeller in said extension, and a clearance space between said reduced end of the inner tube, and said hollow barrel to receive extra leads which become readily accessible upon removal of the tip.

2. In a mechanical pencil, a hollow barrel forming a handle portion, an inner tube held in said barrel and laterally spaced therefrom throughout a portion of its inner end, a tip removably secured at one end of said barrel adjacent said inner end of the inner tube, the space between the inner tube and the barrel forming a magazine for extra leads available upon removal of said tip, and resilient securing means associated with said tip for coaction with the lower end of said hollow barrel to frictionally and removably hold said tip in place thereon.

3. In a pencil, a hollow barrel, an inner tube located within the barrel and having a reduced portion spaced from the interior of the barrel to provide a lead magazine, said inner tube also having an enlarged portion providing an extra lead magazine, and removable closure means for the respective magazines.

In witness whereof, I have hereunto subscribed my name.

JOHN STRAKA.
